HIRAM PARKER, OF SALEM, ASSIGNOR TO H. W. PERSING, OF MARION COUNTY, ILLINOIS.

Letters Patent No. 79,251, dated June 23, 1868.

IMPROVEMENT IN WAGON-BOXES.

The Schedule referred to in these Letters Patent and making part of the same.

TO ALL WHOM IT MAY CONCERN:

Be it known that I, HIRAM PARKER, of Salem, in the county of Marion, State of Illinois, have invented a new and useful Improvement in Wagon-Boxes; and I do declare that the following is a full, clear, and exact description of the construction and operation of the same, reference being had to the accompanying drawings, and to the letters of reference marked thereon, said drawings making a part of this specification.

In these drawings—

Figure 1 represents a top view of a wagon-box, in which A is the bottom of the box, B B the side-boards, and C C the end-gates. The side-boards are provided with hinges *h h h*, which allow them to be laid down inwardly after removing the end-gates C C.

Figure 2 is an end view of a wagon-box, in which C is the end-gate, in position, and B B the side-boards. The nature of my invention consists of the device attached to the end-gate, which device is composed of the eccentric, *a*, rods *b b*, passing through or otherwise attached to the cleats *c c*, staples *d d*, in the side-boards B B, plate *i*, of a triangular or any other suitable form, fastened to the end-gate. The plate *i* has in its centre a stud, *f*, upon which works the eccentric, *a*, secured by means of a nut or pin. Between the eccentric and nut is a rubber washer. The rods *b b* have each on the inner end an eye, which works upon a stud fastened in the eccentric, as shown at *e e*, one above and the other below the centre of the eccentric, *a*. These rods *b b* may, however, be otherwise formed and connected with the eccentric, *a*. The outer ends of the rods *b b* are provided with a hook to work in the staples *d d*. The rods *b b* may, however, be otherwise constructed and arranged to connect with and secure the side-boards B B. The eccentric, *a*, is provided on the inside of the handle, or at any other suitable place, with a pawl, *y*, working in the ratchet *g*. The ratchet may be separate from or it may be attached to and thus form a part of the plate *i*.

The object of this invention is to secure the end-gates C C and the side-boards B B firmly in position, and at the same time allow the end-gates to be easily removed or fixed in place.

This device can be attached to and operated upon any other form or style of wagon-box than the one described and shown by accompanying drawings.

It is operated as follows: The end-gate C, shown in fig. 2, being placed in position between the side-boards B B and the ends of the rods *b b* placed in the staples *d d*, the handle of the eccentric, *a*, is then thrown into the ratchet *g*, and secured in position by the pawl *y*, thus producing a strain upon the rods *b b*, so as to hold the side-boards B B firmly against the end-gate C. To remove the end-gate from the wagon-box, throw the handle of the eccentric from the ratchet, which will remove the strain from the rods *b b*, and thus loosen the hooks in the staples, when the end-gate can readily be removed.

The object of attaching the side-boards B B to the bottom, A, by means of hinges, is, that after removing the end-gates, the side-boards can be laid down inwardly.

What I claim, is—

The combination and arrangement of the eccentric, *a*, working on the stud *f*, the rods *b b*, working in the staples *d d*, the pawl *y*, attached to the handle of the eccentric, *a*, so as to work in the ratchet *g*, substantially in the manner shown and described, and for the purposes above set forth.

In testimony that I claim the foregoing, I have hereunto set my hand, this 3d day of April, 1868.

HIRAM PARKER.
